UNITED STATES PATENT OFFICE.

HOWARD V. HINCKLEY, OF TOPEKA, KANSAS.

APPARATUS FOR DEVELOPING AND REGULATING WATER-SUPPLY.

SPECIFICATION forming part of Letters Patent No. 614,653, dated November 22, 1898.

Application filed October 30, 1897. Serial No. 656,904. (No model.)

To all whom it may concern:

Be it known that I, HOWARD V. HINCKLEY, of Topeka, in the county of Shawnee and State of Kansas, have invented a new and useful Improvement in Apparatus for the Development and Regulation of Water-Supply, of which the following is a specification.

The prime object of my invention is to provide a practical and satisfactory means for drawing water at pleasure from the subterranean flood-plane or underflow, more particularly in arid and semiarid districts, such as exist in some of the Western States and Territories of the United States.

I attain my object by the system or apparatus shown in the accompanying drawings, in which—

Figure 1 is a profile or vertical section of a valley or other sloping country in which I locate a series of wells or cribs to serve as water - collectors connected by pipes that serve as outlets and conveyers. Fig. 2 is a plan of one of such wells, showing devices therein contained for regulating the flow into and from the well. Fig. 3 is a vertical section of well, showing the means for regulating the flow from it into the conduit or conveyer that connects adjacent wells and extends to the common outlet of all the wells. Fig. 4 is a side view of the form of a gate I employ.

Referring to Fig. 1, the wells W are built in the shape of cupolas for the following reasons: The larger the bottom of a well the greater the influx per minute. The smaller the top of the well above ground the less will be the obstruction to the flow of the river in case the well is located within the limits of the river-channel. The smaller the top the less material used in construction. The same reasons apply to the manhole or shaft extending from each crib C to the surface.

M is the manhole or shaft of the cribs C; G, a gravity-conduit that connects adjacent wells. V is a stop gate or valve in such conduit. S is a vertically-sliding gate. K is a gate-box; L, a lift-gate in such box; P, a weight for closing lift-gate; T, a cord, chain, rope, or wire for opening a lift-gate, and H a funnel end of outlet-section of the gravity-conduit.

The wells or cribs, or both, will invariably

be open at the bottom and will invariably be tight on their sides. The wells will have walls of stone, Portland cement, concrete, or 55 brick masonry from top to bottom. The cribs will be of wood and the shafts M may be brick or steel cylinders asphalted. The water-level being normally at A B will be lowered by the efflux from the wells or cribs by way of the 60 conduit G, so that these manhole-shafts and cupolas extending up to the surface will not always be under water, and their construction, therefore, to be permanent must not be of wood unless the latter be creosoted or otherwise preserved.

Referring to Fig. 2, the gate-box K surrounds the ends of both the upper and lower sections of the conduit that enter a well, so that it may exclude water of the well from 70 the conduit entirely. This gate-box K may rest upon two large timbers or two T-rails extending across the well at right angles to the conduit, the ends thereof being embedded in the walls of the well.

If the gate-valve in upstream section of conduit be closed and the slide-gates be closed, no water can run in the downstream section, even though the other gate-valve V be open. It is evident that the object of these two 80 gate-valves is the same; in other words, either of them controls the flow through the conduit from one well to the next. I use one at each end of each conduit-section simply as a matter of safety, since if one is out of order the 85 other can do the work while the first is being repaired; or if the slide-gates S or lift-gate L are out of order the lower gate V may be used either to keep the water quiet by stopping the flow or to open the conduit and so drain 90 the well to the lowest possible limit. With the gate-valves V open and the slide-gates S and lift-gate L closed in a particular well the water in that well remains undisturbed and the water from any well above such one 95 may be made to flow through and past this well without interference. In this way the capacity of any well for furnishing water may be determined by gravity-flow through the conduit. Again, the upper gate-valve 100 V may be closed and the lower one opened, the gates L and S opened, and the capacity of this well be thus tested. By opening gates at pleasure in different wells or cribs any

desired amount of water (within the maximum limit of the entire plant) may be supplied through the conduit to the common point of discharge A. By closing the gate 5 V at lower end of each conduit-section that section may be kept full of water and so, in case of a wooden pipe, be protected from decay. The gate-valve I prefer to have of the common form—such, for example, as the Ludlow flume-valve. (Shown in Fig. 4.) This is geared to turn by a nut over a small toothed wheel. A long iron rod or gas-pipe with square head to fit over this nut and with a wheel or cross-arm on its upper end could 10 rest continually upon this nut with its upper end within reach of the top of the manhole-shaft.

The slide-gates S can be made of any width from a few inches to several feet and may 20 be pulled up and pushed down by a piece of lumber which is the gate itself extended upward to the top of the manhole-shaft. The lift-gate L (shown in Fig. 2) may be one or several gates lifted and weighted same as 25 shown in Fig. 3. The purpose of making the mouth of the lower conduit-section of each well funnel-shaped is this: The water from the upper section of the conduit to the lower in a well meets with no resistance, while the 30 water from such well meets with no resistance in passing into the lower section when the gates S and L are open; but, on the other hand, the water flowing through tends to suck in the water from this well on the principle of 35 an injector. As the gravity-conduit will be an expensive institution and the fall in feet per mile will be light it becomes necessary to attain the highest possible percentage of efficiency, and this the funnel end attains.

40 The bottom of the wall or sides of well or crib will be several feet below the bottom of the excavation inside thereof. This is a precaution necessary to prevent sand from boiling up in the well under pressure of the outside water. The conduit will always be several feet above the bottom of the excavation, so that sand may not be drawn into the conduit by the eddying motion of the water. The 45 conduit may be of dry or cemented masonry, concrete, brick or cement pipe, burned clay sewer-pipe, wrought or cast iron or other metallic pipe, or a lumber flume or boxing, or sheet-piling shored and covered; but it will generally be of wooden-stave pipe girdled 50 with bands or rods of iron, steel, copper, or other metal such as is commonly used and designated as wooden pipe. Tunnels may be run out from the wells or chambers in any direction to assist in collecting the water. The 55 slope of the conduit between the wells or cribs will generally, but not necessarily, be the same slope as that of the country or the surface above them. The wells or cribs, or both, in connection with the conduit, gates, &c., 60 may discharge the developed supply by the

gravity-conduit to the surface of the ground, or, where necessary, a pump or pumps may be erected over or near the lower well or crib in the series, and the water be thus elevated to the surface by mechanical means, or the 70 gravity-conduit may carry the water to some point downstream from the lower well and deliver the water directly to the pump.

In reference to Fig. 1 in the drawings it may be explained that it necessarily shows 75 the wells arranged on somewhat exaggerated vertical scale, since otherwise the outlet A could not be shown. The wells do not extend in a straight line up and down the river-bed. In some arid regions there are water-slopes, 80 at a right angle to the direction of the river, as steep as thirty feet to the mile, as has been determined by my own measurements. The line of wells may or may not follow the river course. There are localities where the slope 85 of the surface is many times steeper and the water-supply is many times greater up the lateral slopes than up the river-bed. The wells need not be below or lower than any river-bed. They must be below the water- 90 level—i. e., submerged.

What I claim is—

1. In a subterranean water-supply apparatus the combination with a well or water-collecting chamber of a box provided with inlet-valves and located in said well and supported above the bottom thereof, an eduction-water conduit leading out of said box, and having a funnel-mouth within the latter, and a second or induction conduit which leads into the 100 box and enters the mouth of the lower conduit, as shown and described.

2. A water-supply apparatus consisting of two or more cupola-shaped wells, or cribs, with connecting-conduits, all located and 105 submerged in a natural reservoir of subterranean water and provided with a gravity-discharge as described, for the purpose of developing and regulating the supply of underground water.

3. A water-supply apparatus consisting of a submerged well or crib, having a cupola or manhole-shaft M, an induction-gravity conduit having a funnel end H, and the gate-valve V, as shown and described, for developing 115 and regulating the supply of water underground, as shown and described.

4. The combination of a series of submerged wells, or cribs, and a series of inclined conduits connecting the same for drawing off the water therefrom, by gravity, gate-valves V, located in such conduits, a box having slide-gates, and lift-gates, and means for operating such gates, as shown and described for the purpose of developing and regulating the flow 125 of underground water.
